UNITED STATES PATENT OFFICE.

DOCTOR ROBERT L. BOYD, OF SUMRALL, MISSISSIPPI.

RAILROAD CROSS-TIE.

No. 876,140.

Specification of Letters Patent.

Patented Jan. 7, 1908.

Application filed January 14, 1907. Serial No. 352,266.

To all whom it may concern:

Be it known that I, DOCTOR R. L. BOYD, a citizen of the United States, residing at Sumrall, in the county of Lamar and State of Mississippi, have invented a new and useful Improvement in a Railroad Cross-Tie, of which the following is a specification.

This invention relates to metallic railroad ties, the object being to provide a metallic tie with a wooden cushion so as to form a cushion to relieve the rails of the strain.

Another object of my invention is to provide very novel means for securing the wooden blocks in the tie.

Another object of my invention is to provide the tie with means for preventing the rails from spreading when secured thereon.

With these and other objects in view, the invention consists in the novel features of construction, combination and arrangement of parts hereinafter fully described and pointed out in the claims.

In the drawings forming a part of this specification:—Figure 1 is a side view of my improved tie showing the rails arranged thereon. Fig. 2 is a top plan view of the tie. Fig. 3 is a longitudinal sectional view of the tie.

In the drawing A indicates a trough-shaped metal tie provided with downwardly extending sides A' and ends A² adapted to be embedded in the ground, so as to prevent all danger of the tie moving. The sides of the tie are of a greater depth at their center, so as to strengthen the same, and prevent all danger of the tie buckling. The ends of the trough extend inwardly as shown at A³ under which extend the ends of wooden blocks B arranged in the trough at each end. The blocks are provided with transverse bores adjacent their inner ends, in alinement with openings in the oppositely disposed apertured lugs A⁴, projecting up from the side of the trough adjacent each end through which

extend bolts C, which securely lock the blocks in the trough. Upwardly projecting oppositely disposed lugs A⁵ are formed on the side of the trough between the apertured lugs and ends forming stops for the rails secured on the block in the ordinary manner, for preventing the rails from spreading.

Having thus fully described my invention, what I claim as new and desire to secure by Letters Patent is:—

1. A trough shaped tie provided with inwardly projecting ends, and upwardly extending spaced lugs on its sides.

2. The combination with a trough-shaped tie provided with inwardly projecting ends, of wooden blocks arranged in said tie under said ends and means for securing said block in said tie.

3. The combination with a trough-shaped tie provided with downwardly projecting sides and ends, of wood blocks arranged in said tie at each end, inwardly projecting portions formed on the ends extending over said blocks and spaced lugs formed on said sides projecting up above said blocks.

4. The combination with a trough-shaped tie provided with inwardly projecting ends, of blocks extending under said ends, apertured lugs formed on the sides of the tie, lugs projecting up from the side of the tie above said blocks and bolts extending through said apertured lugs and blocks, for the purpose described.

5. A metal trough-shaped tie provided with inwardly projecting ends, of wooden blocks arranged in said tie extending under said ends, provided with transverse bores, apertured lugs projecting up from the side of the tie and a bolt extending through said lugs and blocks.

DOCTOR ROBT. L. BOYD.
